UNITED STATES PATENT OFFICE.

ROBERT FLECK, OF CARDOWAN, NEAR STEPPS, SCOTLAND.

ADJUSTABLE SPANNER.

1,158,913.

Specification of Letters Patent.

Patented Nov. 2, 1915.

Application filed August 19, 1914. Serial No. 857,441.

To all whom it may concern:

Be it known that I, ROBERT FLECK, a subject of the King of Great Britain, residing at Cardowan, near Stepps, Lanarkshire, Scotland, have invented certain new and useful Improvements in Adjustable Spanners, of which the following is a specification.

This invention relates to adjustable spanners of the type wherein one jaw is formed 10 in a handle or body portion while the other jaw, which is movable or adjustable, is mounted on or in the handle or body portion and can be adjusted parallel with the other jaw by an adjusting screw which engages with the movable or adjustable jaw and with the handle or body portion.

Under my invention, the spanner is constituted by a number of known parts constructed, arranged and combined together 20 substantially as hereinafter set forth, comprising a handle member or body part and a movable member or movable part, the handle or body part having a projection or jaw, a bearing surface and a block or projection, while the movable part has a projection or jaw, a projection or toe piece, a shoulder and a contact part, the parts being 25 retained adjustably in position by screw or equivalent means. The adjustment of the 30 parts may be facilitated, if desired, by spring or equivalent means.

The parts may be so arranged to constitute a single-ended spanner, or if desired, by the duplication of certain of the parts a 35 double-ended spanner may be constituted.

In order that my said invention may be properly understood I have hereunto appended two explanatory sheets of drawings whereon various forms of my adjustable 40 spanner are illustrated.

On the drawings:—Figures 1 and 2 show a plan view and side view, respectively, of one form of single-ended spanner. Fig. 3 is another plan view of the same spanner. 45 Fig. 4 is a plan view of a double-ended spanner. Figs. 5 and 6 show a plan view (partly in section) and side view, respectively, of another modified form of single-ended spanner. Fig. 7 is a side view of the body or under part *a*, of the spanner illustrated at Figs. 6 and 7, and Fig. 8 is a side view of the upper part or removable jaw *c*. 50 Fig. 9 is a plan view, partly in section, of

another slightly modified construction of spanner.

55

On the drawings the same reference letters wherever repeated indicate the same or similar parts.

In carrying out my invention in the case of a single-ended spanner, as illustrated 60 at Figs. 1, 2 and 3 the body of the spanner comprises two parts one working on the other. The one part, which may be termed the handle member or body part *a*, is provided with a suitably shaped projection or 65 jaw *b* at one end, while the other part, which may be termed the movable member or movable part *c*, can be moved on the body *a* and is likewise provided with a projection or jaw *b*¹ at one end, the arrangement being 70 such that the two projections or jaws *b*, *b*¹ work in conjunction with each other and form the head or gripping portion of the spanner.

The head or gripping portion of the span- 75 ner is made with a suitable bearing surface, or surfaces *d*, so that the part *c*¹ of the movable part *c* when the latter is placed in position on the body *a*, will be in sliding contact therewith and the distance between the 80 projections or jaws *b*, *b*¹, can be varied when required by moving the movable member or movable part *c* in the desired direction.

When it is desired to decrease the distance between the projections or jaws *b*, *b*¹, a 85 pinching screw device such as illustrated, is preferably used. This device consists of an adjusting screw *e* working in a block or projection *f* which may be either secured to or made one with the body *a*. By operating 90 the screw *e* in one direction one end of said screw bears on a projection or toe piece *g* formed on the movable part *c* thereby causing it to slide over the body *a* until the desired size of opening between the projec- 95 tions or jaws *b*, *b*¹, is obtained, whereupon the spanner can be used in the ordinary manner. When the spanner is in use and pressure comes on the projection or jaw *b*¹, say when screwing up a nut or such like, 100 said pressure is communicated to the block or projection *f* through the shoulder *h* of the movable part *c* and the point of contact of the shoulder *h* with the block or projection *f* becomes the center of a radial movement 105 which causes the part *c*¹ to press angularly

on the bearing surface *d*, and the shoulder *h* to press angularly on the block or projection *f* thereby preventing the slackening of the projections or jaws *b*, *b*¹. By operating the screw *e* in the other direction the end thereof is moved out of contact with the projection or toe piece *g* on the movable part *c* so that said part can be readily moved or shifted to increase the size of opening between the projections or jaws *b*, *b*¹. This movement of the movable part *c* may be, as shown at Figs. 1, 2 and 3 and also Figs. 4 and 5 facilitated by means of a plate spring or its equivalent *i* one end of which is suitably secured to the projection or jaw *b* while its other end bears on the side of the movable part *c*. The arrangement of the spring or its equivalent *i*, when used, is such that, it normally tends to push the movable part *c* into its extended position, as indicated in dotted lines at Fig. 3.

The handle or body part *a* and the movable part *c* of the spanner can be retained in sliding contact with each other in any suitable manner. In Figs. 1, 2, 3 and 4 a slot *j* is made in the movable part *c*, while, passing through the slot *j* is a screw or the like *k* fitted in the handle or body part *a*. The head of the screw or the like *k* projects over the slot *j* in such manner as to hold the parts *a*, *c*, in contact while permitting the necessary sliding movement to take place. If desired, the arrangement may be reversed, the slot being made in the body or under part *a*.

In Fig. 4 a double-ended spanner is illustrated, the arrangement of parts being similar to that of the spanner described with reference to the preceding figures. It will be noted that one of the screws *e* requires to be reversed in order that it may operate in the required manner, as previously described.

In the modified construction of spanner illustrated at Figs. 5, 6, 7 and 8 the body part *a* is made of slotted formation at one end as indicated at *m* for the reception of the movable part *c* so that when the part *c* is inserted in the slotted portion *m* the two sides thereof form a guide for same. With this arrangement when fitting the parts together, the movable part *c* is inserted in the slotted portion *m* and the block *f* carrying the screw *e* is thereafter placed in position and secured in place by means of a rivet, pin, or other suitable securing means *n*. The slotted portion *m* may be slightly enlarged at its inner end for the reception of the block *f*.

If desired the block *f*, instead of being made separate and secured in place as in the arrangement illustrated at Figs. 5, 6, 7 and 8, may be formed integral with the body part *a*, in which case the construction of the spanner would preferably be as illustrated at Fig. 9. When fitting the parts to-

gether, the movable part *c* is inserted in the slotted portion *m*, to a position as shown in dotted lines, and is thereafter turned down into the slot, the toe-piece *g* clearing the block or projection *f* and the part *c* assuming the correct position shown in full lines. A screw or pin *k* is then inserted in openings in the handle member so as to pass through the slot *j* in the movable part. As in the other arrangements, a spring may be used to facilitate the movements of the part *c*.
70
75

The parts constituting the body of the spanner may be cast or otherwise formed.

Having now fully described my invention 80 what I claim and desire to secure by Letters Patent is:—

1. An adjustable spanner comprising a handle member and a movable member; a jaw and a pressure block on the handle member forming bearing surfaces for the movable member which is adapted to slide therebetween; a jaw and a toe-piece on the movable member; screw means adapted to coact with said pressure block and said toe-piece; and a projection carried by one member adapted to engage a slot in the other member for locking the parts in position.
85
90

2. An adjustable spanner comprising a body part and a plurality of movable parts; 95 jaws and pressure blocks on the body part forming bearing surfaces for the movable parts; a jaw and a toe-piece on each movable part; screw means adapted to coact with said pressure blocks and said toe-100 pieces; and means for locking the parts in position.

3. An adjustable spanner comprising a handle member and a movable member; a jaw and a pressure block on the handle member forming bearing surfaces for the movable member which is adapted to slide therebetween; a jaw and a toe-piece on the movable members; screw means adapted to coact with said pressure block and said toe-piece; a projection carried by one member adapted to engage a slot in the other member; and spring means for facilitating movement of the movable member.
105
110

4. An adjustable spanner comprising a body part and a plurality of movable parts; jaws and pressure blocks on the body part forming bearing surfaces for the movable parts; a jaw and a toe-piece on each movable member; screw means adapted to coact with said pressure blocks and said toe-pieces; means for locking the parts in position, and spring means for facilitating movement of the movable parts.
115
120

5. An adjustable spanner comprising a handle member having a jaw formed integral therewith and a transverse slot extending through the member, a movable member having a jaw and a toe-piece formed integral therewith adapted to slide in said 125
130

slot, screw means carried by the handle member adapted to engage said toe-piece, and a projection carried by one member adapted to engage a slot in the other member.

6. An adjustable spanner comprising a handle member having a jaw formed integral therewith and a transverse slot extending through the member, a movable member having a jaw and a toe-piece formed integral therewith adapted to slide in said slot; screw means carried by the handle member adapted to engage said toe-piece, a projection carried by one member adapted to engage a slot in the other member, and spring means for facilitating movement of the movable member.

7. An adjustable spanner comprising a handle member having a jaw formed integral therewith and a transverse slot extending through the member, a pressure block secured in said slot, a movable member having a jaw and a toe-piece formed integral therewith adapted to slide in said slot;

Copies of this patent may be obtained for five cents each, by addressing the "Commissioner of Patents, Washington, D. C."

screw means carried by the pressure block 25 adapted to engage said toe-piece, and a projection carried by one member adapted to engage a slot in the other member.

8. An adjustable spanner comprising a handle member having a jaw formed integral therewith and a transverse slot extending through the member, a pressure block secured in said slot, a movable member having a jaw and a toe-piece formed integral therewith adapted to slide in said slot; 30 screw means carried by the pressure block adapted to engage said toe-piece, a projection carried by one member adapted to engage a slot in the other member, and spring means for facilitating movement of the 35 movable member.

In testimony whereof I affix my signature in presence of two witnesses.

ROBERT FLECK.
